UNITED STATES PATENT OFFICE.

DOMNICK KULAGE AND RICHARD O. OAKLEY, OF ST. LOUIS, MISSOURI, ASSIGNEES TO
PEERLESS WEATHERSTRIP AND CAULKING COMPANY, OF ST. LOUIS, MISSOURI,
A CORPORATION OF MISSOURI.

WEATHER STRIP.

Application filed January 5, 1924. Serial No. 684,499.

To all whom it may concern:

Be it known that we, DOMNICK KULAGE and RICHARD O. OAKLEY, citizens of the United States, residing at the city of St. Louis, in the State of Missouri, have invented certain new and useful Improvements in Weather Strips, of which the following is a specification.

This invention relates to weather-strips, and, in its most important aspect, pertains more specifically to certain new and useful improvements in weather-strips of the slot-and-tongue type adapted to compensate for undue shrinkage of the window-sashes and the like to which they are applicable.

Hitherto, this type of strip has consisted of three parts, and one of the objects of the present invention is to simplify this construction so that but two parts are necessary.

Another object is to provide a standard form of strip which is readily applicable to windows and the like of various sizes.

Another object is to increase the length of, and provide irregularities in the path traversed by any leakage of air, and thereby impede and mitigate the flow of air through such path.

Other objects will appear in the course of the following description.

In the accompanying drawings forming part of this specification, in which like numbers of reference denote like parts wherever they occur,

Figure 1 is a horizontal sectional view on the irregular line 1—1 of Figure 2, of a window-frame and sash to which the weather-strip of this invention has been applied; and

Figure 2 is a fragmentary vertical sectional view taken on the irregular line 2—2 of Figure 1.

A window-frame 1 has the conventional parting bead 2 between the inner sash runway 3 and the outer sash runway 4, and, also, has the inside bead 5 for confining the sash 6 within proper bounds. The window-sash 6 is of the usual type and contains the glass pane 7 secured to the sash 6 by the bead 8.

In equipping a window with this invention, the parting bead 2 is removed, and a slot 9 is formed in its inner side 10, for the reception of one end of the weather-strip 11.

The inside bead 5 is removed for the purpose of planing a recess 12 on the inner half 55 of its rear to provide a seat for the other end or edge of the strip 11. The window-sash is next removed and the bead 2 replaced in the frame and strip 11 inserted in slot 9. The strip 11 may be of any suitable 60 material, and consists of a web portion 13 having its free edge 14 inserted in the recess 12 and terminating at its other edge in a half-turn bend 15 abutting against side 10, and of a portion 16 continuing from said 65 bend 15 substantially parallel and oppositely disposed to web 13 in typical channel fashion to form a slot 17 therebetween and bending back upon itself at 18 and terminating in end or edge 19 projecting slightly beyond the bend 15 into the slot 9.

A deep and narrow longitudinal slot 20 is cut in the narrow or runway side 21 of the sash 6, preferably approximately three-eighths of an inch from the outside face 22 75 of the sash, and a recess 23 of less depth is made in the sides 21 between the slot 20 and face 22. Another weather-strip 24, of L-shaped cross-section, and preferably of metal, has a wide flange 25 and a narrow 80 flange 26. The wide flange or tongue 25 is of such thickness as to make a slidable but sufficiently air-tight fit in the slot 20. Flange 25 is provided with transverse slots 27. Flange 26 is inserted in the slot 20, so 85 that flange 26 extends outwardly, and pins 28 are driven through the sash 6 across the slot 20 and through the slots 27. The pins 28 co-operating with the slots 27 permit lateral movement of the strip 24, but prevent 90 undue longitudinal movement of the said strip in the slot 20. Sash 6 is now replaced in its proper position in the window-frame 1, care being taken that flange 26 passes between the web 13 and the flange 16 of strip 95 11. Stop bead 5 is next secured in place in the frame 1 by any suitable fastening means, the edge or end 14 of strip 11 being clamped and held between the bead 5 and the frame 1.

The usual type of weather-strip 29 may be used at the sill 30 of the frame 1, and fits in the usual slot 31 in the bottom 32 of the window-sash 6. Such a strip 29 is thinner than the slot 31, except at the end 33, where it makes what is merely a line contact with 100 the sides 34 of the slot 31. On the sides of

the window, however, the use of such a strip would result in excessive leakage in the event of undue shrinkage of the sash.

It is manifest that the lateral movement 5 of the tongue 25 in the slot 20 in the sash 6 takes care of any undue shrinkage of the window-sash that might occur in use, such slot and tongue construction in itself, however, being contemplated prior to the pres-

10 ent invention.

It is further manifest that only one other strip, that is the strip 11, is needed in the present invention to co-operate with the strip 24. It is obvious that any space existing 15 between flange 26 and web 13 or flange 16, in the event of there being no intimate contact of flange 26 with either web 13 or flange 16, is extremely attenuated because of the narrowness of the slot 17, and, also, 20 relatively long because of the width of the flanges 16 and 26, and both these features of construction, in conjunction with the irregularities, such as the bends 15 and 18, offer obstruction and impedance to the free 25 flow of air through the said spaces or cracks.

It is, also, to be noted that the strip 11 is universally applicable to beads 2, no matter what variation there may be, between frames of different sizes or makes, in respect to the 30 depth to which bead 2 extends into the frame 1.

It is, also, obvious that this invention is not necessarily restricted to the use of the strip 24 of L-shaped cross-section, but any 35 suitable strip secured in a suitable manner

to the sash 6 and having an edge projecting into the slot 17 may be used in lieu thereof.

Having thus described this invention, we hereby reserve the benefit of all changes in form, arrangement, order, or use of parts, 40 as it is evident that many minor changes may be made therein without departing from the spirit of this invention or the scope of the following claim.

45 We claim:

The combination with a window frame having an inside bead—a parting bead provided with a recess extending longitudinally of its inner face but spaced outwardly from the side of the frame—and a sliding sash between the said beads, of a weatherstrip having its inner longitudinal edge seated in the said recess of the parting bead and its outer longitudinal edge secured between the said inside bead and the adjacent face of the said frame, said weatherstrip having the portion between the said beads lying flat against the side of the said frame and being provided with a channel-forming bend in the portion 55 adjacent the said parting bead, and a second weatherstrip of L-shaped cross-section and uniform thickness having one leg adjustably secured to the said sliding sash and the other leg engaged in the channel of the first-mentioned strip.

60 In testimony whereof we hereunto affix our signatures.

DOMNICK KULAGE.
RICHARD O. OAKLEY.
